UNITED STATES PATENT OFFICE

DAVID B. WHISTLER, OF DAYTON, OHIO, ASSIGNOR TO THE BLACK-CLAWSON COMPANY, OF HAMILTON, OHIO

APPARATUS AND METHOD FOR MAKING PULP OR THE LIKE

Application filed May 31, 1928. Serial No. 281,633.

This invention relates to improvements in apparatus and method for making pulp.

In the accompanying drawings which serve for illustrating the invention:

5 Fig. 1 is a plan view of a stock beater equipped with an attachment for removing foreign materials from the raw stock;

Fig. 2 is a detail sectional view of Fig. 1.

10 Fig. 3 is a sectional view similar to Fig. 2 showing a modification.

Fig. 4 is a plan view of the apparatus including a prehydrating tank for the raw stock;

15 Fig. 5 is a sectional view on line 5—5 of Fig. 4.

Fig. 6 is a detail plan view similar to Fig. 4 with the operating parts removed;

20 Figs. 7—8 are detail views of parts of the mechanism.

25 In making pulp from old paper and rag stocks with ordinary reduction apparatus, irreducible foreign matter in the stock, as scraps of metal, glass, etc., commonly designated as junk, settles in the stock beater and other units of the machinery and interferes with production. The accumulation of the 30 junk necessitates frequent shutting down of the machinery for removing it. This hindrance and retardation of reduction is of such consequence that it influences the cost of production very materially and is besides a disagreeable condition from the viewpoint of manual labor required for removing the junk from the reduction apparatus.

35 In recent years junk removers operably associated with the stock beater, or breaker, have come into extensive use and have been helpful towards effecting more favorable conditions of operation and increasing production.

40 An object attained in the present invention consists in providing means for breaking up the bales or mass of raw stock, for pre-hydrating the stock, and incidentally, for removing therefrom the greater portion of the foreign materials which settle in the hydrating tank before the stock is delivered into the beater or breaker.

45 A further object attained in the invention 50 consists in also providing improved means

operably associated with the stock beater for removing any portion of the junk remaining in the stock as delivered to the beater from the hydrating tank. One or more of the improved junk removers operably associated with the stock beater, irrespective of the hydrating tank and its junk remover attachment, will be effective for removing the junk from raw stock delivered direct into the beater, but with the usual run of old paper and rag stock pre-hydrating of the stock and removal therefrom of the coarser foreign substances will be preferred.

To this end, the improved apparatus includes an ordinary stock beater comprising 55 the tub 1, beater roll 2, midfeather 3, beater roll shaft 4, and belt drive pulley 5, the showing in the drawings of these parts being more or less conventional for illustrating the relation of the junk removing attachment thereto. 60

The junk remover which is here shown in two units, consists of outward cylindrical extensions 6 of the beater tub, forming wells 7 which extend substantially below the beater tub bottom which communicates with the 75 wells by downwardly inclined recesses 8, and apertures 9 opening into the wells. Supported rotatably in each of the wells is a vertically extended feed screw 10 which is supported at its lower end in a bearing 11, 80 at its upper end in a bearing 12, and is connected to the beater roll shaft by gears 13—14, a shaft 15 and gears 16—17. The gears may be at any ratio one to another for effecting the desired speed of the feed screw. 85

It will be seen that junk settling in the beater tub will be washed by the mass movement of the stock in process of hydration and beating therein into the inclined recesses 8 in the bottom of the tub and thence into the 90 wells 7 where it will be taken up by the feed screw and discharged at the sides of the well through a chute 18 into any suitable receptacle for receiving it. The bottoms of the wells 7 are provided, as here shown, with annular grooves 19 into which fingers 20 at the lower, forward edge of the feed screw extend, the arrangement serving to aid the feed screw to take up the junk and to prevent 95 clogging in the bottom of the well. 100

Any suitable means, as the water pipes 21, may be provided for flushing the junk wells, and for supplying the beater with water as required for hydrating the pulp stock. As 5 the stock floats at the higher levels in the beater tub, only white water, or water having a small percentage of fine pulp suspended therein, enters the junk wells. The discharge of water from pipes 21, required for hydrating 10 the pulp stock, directed on the junk as it is moved upward on the screw feed, washes off the adhering pulp. A port 22 in the beater tub wall between the beater and the well above the level of the pulp stock in the beater serves for returning the pulp washed 15 from the junk to the beater.

The modified construction, illustrated in Fig. 3 is like that shown in Fig. 1-2, except that the well 23 and feed screw 27 are inclined 20 at a suitable angle for favoring the action of the screw on the junk. Parts 23-34 of the modified form are similar in construction and function of operation to the corresponding parts illustrated and described in connection 25 with Figs. 1-2.

The junk remover used in combination with a fine pulp extractor (not shown) makes a highly effective apparatus for continuous operation in the processes of producing pulp. 30 The continuous extraction or separation of the fine pulp serves to prevent over reduction of the portions of the stock which respond more readily to hydration and beating, and results in producing a more uniform grade 35 and a better quality of pulp. Fine pulp extractors in various forms are well known in the art and are adapted to be used with the stock beater and junk remover, as herein shown and described, in their usual construction. 40

The apparatus as shown in Figs. 4-8 of the drawings may include one or more of the junk remover units as shown in Figs. 2 or 3 operatively associated direct with the stock beater as indicated at 6. On the opposite side of the beater, as here shown, is a tank 35 for receiving the raw stock which is broken up from its compact bulk in the bales and subjected to hydration before it passes to 45 the beater, the movement of the stock from the tank 35 to the beater being regulated by a gate 45 according to the requirements. The stock is broken up in tank 35 by opposite sets of breaker blades 36 which are fixed on inclined shafts 37 operable in bearings 51-52 of opposite breaker base walls 53 having clearance spaces 54 for the blades 36, the adjacent edges of the clearance spaces acting to prevent clogging of the blades by the 55 stock.

The shafts 37 are driven from the beater roll shaft 38 through bevel gears 38-39, 40-41, 42-43, and the gear shaft 44, in opposite directions one shaft to the other, the 60 blades 36 being arranged on the shafts alter-

nately one blade with another of the opposed sets with their planes of rotation intersecting and one set of arms passing through the zone of intersection, as here shown, in unison with the other. Thus the blades 36 70 which have dull forward edges 36a act on the stock to break up the bulk of the bales, and to reduce the mass to a state of uniform hydration before the stock passes through the gate 45 to the beater. 75

Breaking up of the raw stock in the hydrating tank 35 also results in separating therefrom a large portion of the heavy foreign substances which gravitate to the bottom of the tank which is inclined downward, as here shown, toward the beater, thus causing the junk to move to the lowest point in the tank and thence through an inclined passage 46 into the bottom of a well 47 from which the accumulation is removed by a feed screw 48 in the manner described in connection with the structure shown in Figs. 1-3, the feed screw being operably connected to shaft 44 by gears 49-50. 80

Removal of the greater portion of the 90 junk from the raw stock and hydration of the stock before it enters the beater materially facilitates the further reduction in the beater. The removal of the coarser junk in the hydrating tank also has the further beneficial effect of protecting the blades of the beater roll which are injured more or less by such substances and require frequent replacement when the junk is not removed before the raw stock is supplied to the beater. 95

The lesser and finer portion of the junk which enters the beater from the hydrating tank will be removed by the junk remover 6 which is operably associated with the beater. Thus continuous operation with material increase in production is made possible by the 100 improved apparatus.

While the stock breaker blades 36 of each set are shown and described in connection with Fig. 4 as being in line one with the other on their operating shafts and the opposite sets operating in unison one set with the other, the blades of each set may be in staggered relation one with another as illustrated in Fig. 8 without materially affecting their 110 action on the stock. In the latter arrangement the load and operating power would be more evenly distributed.

As far as I am aware, the apparatus herein 1 set forth is the first of its kind in the art which embodies a hydrating tank operably associated with a stock beater, having means for breaking up and hydrating the raw stock and for removing the greater portion of the foreign substances from the stock before it enters the beater. The development represents a distinct and marked advance in the art of making pulp and I claim the invention, as defined in the appended claims, 1 broadly as to the principal of the apparatus

and also as to the method involved in the practice of the invention, irrespective of the specific structure of the apparatus shown in the drawings for illustrating the invention.

5 I claim as my invention:

1. An apparatus for reducing pulp including in combination with a stock beater, a tank operably associated with the beater, means in the tank for breaking up and hydrating the raw stock before it enters the beater, and means operably associated with said tank for removing foreign substances separated from the stock incidental to said actions thereon.

10 2. An apparatus for reducing pulp including in combination with a stock beater, a tank operably associated with the beater, means in the tank for breaking up and hydrating the raw stock before it enters the beater, means in the tank for causing foreign substances separated from the stock incidental to said actions thereon to gravitate to a common level, and means operably associated with the tank for removing said substances.

15 3. An apparatus for reducing pulp including in combination with a stock beater, a tank operably associated with the beater, means in the tank for breaking up and hydrating the raw stock before it enters the beater, means operably associated with said tank for removing foreign substances separated from the stock incidental to said actions thereon, and means between the tank and beater for regulating the supply of the stock to the beater.

20 35 4. An apparatus for reducing pulp including in combination, a tank operably associated with a stock beater, means in the tank for hydrating the raw stock including a plurality of sets of rotatable members operably opposed one set to another for breaking up the stock, and means operably associated with said tank for removing foreign substances separated from the stock incidental to said actions thereon.

40 45 5. An apparatus for reducing pulp including in combination, a tank operable associated with a stock beater, means in the tank for hydrating the raw stock including a plurality of sets of members, each set supported on a rotatable shaft inclined downward in the direction of movement of the stock and operably opposed one set to another for breaking up the stock, and means operably associated with said tank for removing foreign substances separated from the stock incidental to said actions thereon.

50 55 6. An apparatus for reducing pulp including in combination, a tank operably associated with a stock beater, means in the tank for hydrating the raw stock including a plurality of sets of rotatable members operably connected to the stock beater and operably opposed one set to another for breaking up the stock, and means operably associated with said tank for removing foreign sub-

stances separated from the stock incidental to said actions thereon.

7. An apparatus for reducing pulp including in combination with a stock beater, a tank operably associated with the beater, means in the tank for breaking up and hydrating the raw stock before it enters the beater, means operably associated with said tank for removing foreign substances separated from the stock incidental to said actions thereon, and means operably associated with the stock beater for removing therefrom foreign substances remaining in the stock delivered thereto from said tank.

10 15 8. An apparatus for reducing pulp including a pre-hydrating tank for raw stock operably associated with a stock beater, means in said tank for breaking up the raw stocks including a plurality of rotatable blades for breaking up the bulk of the stock and a breaker head coacting with the blades and acting to prevent clogging thereof by the stock.

15 20 25 9. A process for making pulp consisting in partially breaking up and hydrating raw pulp stock prior to its reduction to pulp, in removing foreign substances separated therefrom by gravity incidental to, and concurrently with, the hydrating and breaking action thereon, in subsequently removing the stock so treated and then subjecting it to a beating action to reduce it to pulp.

25 30 35 10. A process for making pulp consisting in partially breaking up and hydrating raw pulp stock prior to its reduction to pulp, in removing foreign substances separated therefrom by gravity incidental to and concurrently with the hydrating and breaking action thereon, in subsequently removing the stock so treated and subjecting it to a beating action to reduce it to pulp, and in further removing foreign substances separated therefrom by gravity incidental to and concurrently with said beating action thereon.

40 In testimony whereof, I affix my signature.

DAVID B. WHISTLER.
